Inventor:

Emil W. K. Roe
by Miss Elv. Roe

UNITED STATES PATENT OFFICE.

EMIL W. K. ROE, OF CHICAGO, ILLINOIS, ASSIGNOR TO THE ALDON COMPANY, OF CHICAGO, ILLINOIS, A CORPORATION OF ILLINOIS.

CAR-REPLACER.

1,329,854.

Specification of Letters Patent.

Patented Feb. 3, 1920.

Application filed June 19, 1919. Serial No. 305,349.

To all whom it may concern:

Be it known that I, EMIL W. K. ROE, a citizen of the United States, residing at Chicago, in the county of Cook and State 5 of Illinois, have invented certain new and useful Improvements in Car-Replacers, of which the following is a specification.

The object of this invention is to improve that type of car replacer disclosed in U. 10 S. Patent No. 789,384 granted to me May 9, 1905, as Emil W. Rosenberg (since changed by formal court proceedings), to adapt the device for the increased size and weight of modern locomotives, tenders and 15 cars.

A further object of the invention is to reinforce and strengthen a car replacer against the wear of the flange of the wheels and to accommodate locomotives, tenders 20 and cars of the largest size and weight without adding materially to the cost and weight of the replacer.

In the accompanying drawings illustrating a preferred embodiment of the invention,

Figure 1 is a top plan view.

Fig. 2 is a side elevation.

Figs. 3, 4, and 5 are sectional views on the lines 3-3, 4-4, and 5-5 respectively 30 of Fig. 1.

Referring to the drawings the frog has a low front end 10 to receive the wheel and gradually increases in height to the rear end 11 so that when the wheels traveling 35 on a pair of frogs are elevated above the rails sufficiently they may slide laterally from the frogs onto the rails. In practice I employ a pair of frogs for re-railing a car, these frogs being constructed alike 40 except that the position of the flange and the tread riding surfaces thereon is reversed. The tread surface 12 is higher than the flange surface 13. These surfaces are separated by a substantially perpendicular 45 shoulder 14 which, in the preferred embodiment of the invention, extends lengthwise of the frog from a point adjacent one corner of the front end of the frog diagonally to a point near the opposite corner of the 50 rear end of the frog. Therefore, the tread surface is narrow at its front end and wide at its rear end, and the flange surface is wide at its front end and narrow at its rear end. The shoulder 14 preferably increases

gradually in height from the front to the 55 rear end of the frog, and the tread surface is sloped or rounded off at the high portion of the frog from the shoulder to the left side of the frog, and the flange surface is sloped or rounded off at the high portion 60 of the frog from the shoulder to the right side of the frog, as clearly indicated in Figs. 3-5. Cross webs 17 are located at spaced intervals within the frog between its ends to reinforce and strengthen the rod transversely.

In practice the flange of the wheel traveling on the frog always engages the flange surface 13 adjacent the shoulder 14. As the wheel flanges often get to be 70 comparatively sharp and as locomotives, tenders and cars have increased greatly in size and weight I have found in some cases that the wheel flanges will wear or break through the flange surface of the frog. This is 75 due not only to the comparative sharpness of the wheel flange and the weight borne thereby, but also to the usual wear on the frog and largely because in efforts to re-rail a locomotive it very often happens that 80 the wheel is permitted to spin on the frog. As will be readily understood a very little spinning of a modern locomotive wheel on a frog will drive the flange of the wheel through the surface of the frog, and perhaps cause a complete collapse of the frog. Since locomotives are supplied with frogs because the necessity for the use thereof may occur at remote points on the line of travel, it is important to provide a frog 85 which will stand up in service under the unusual conditions to which they are now often subjected and this is the primary object of my present improvement which comprises a rib 18 extending longitudinally 90 of the frog, on the inside thereof, and located beneath the wheel flange wearing surface on the flange surface 13 adjacent the shoulder 14. This rib follows the diagonal direction of the shoulder 14 and, as before 100 stated, is located beneath that portion of the tread surface which is engaged by the flange of the wheel in its travel on the frog, and which portion is located adjacent the longitudinal shoulder 14. This rib is 105 wider in cross section where it merges into the top of the frog than at its lower edge, this being a preferred construction since it

provides a comparatively wide reinforcement with a minimum weight of metal. The longitudinal rib may be of the same height throughout or it may vary in height as may be desirable in a proper proportion of parts and distribution of metal.

My improvement provides increased strength and increased wearing surface at that portion of the frog which requires the greatest strength and which receives the greatest wear, and this reinforcement is so disposed that the desired result is accomplished without any material increase in the cost of manufacture or in weight of metal embodied in the frog. The entire frog may be made in one casting without any movable parts and practical experience has demonstrated to me that this reinforcement and additional wearing surface will accommodate the frog to modern locomotives, tenders and cars and provide that additional wearing surface which enables the frog to stand up and serve its purpose under the conditions of ill usage which frequently result, unintentionally of course, in the use of frogs for re-railing purposes.

Reserving the right to make whatever changes in the form, proportion and dimensions of the parts of my improved frog as fairly come within the scope of the following claims.

What I claim is:

1. A car replacer having an inclined top comprising two separate surfaces, one higher than the other, an intermediate longitudinally extending shoulder between said surfaces, and a rib located under that portion of the lower surface which lies adjacent to said shoulder. 35
2. A car replacer having an inclined top comprising two separate surfaces, one higher than the other, a diagonally extending shoulder extending from end to end of the replacer between said surfaces, and a diagonal rib located under that portion of 45 the lower surface which lies adjacent to said shoulder.
3. A car replacer having an inclined top comprising two separate surfaces, one higher than the other, a diagonal shoulder 50 between said surfaces and extending from end to end of the replacer, and a vertically disposed rib located under that portion of the top which lies adjacent to said shoulder, 55 said rib being integral with said top and wider at its juncture with said top than at its lower edge.

EMIL W. K. ROE.
